(57) **CLAIM**

The ornamental design for a point of care cart-based ultrasound, as shown.

DESCRIPTION

FIG. 1 is a perspective view showing my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The portions of the point of care cart-based ultrasound shown in broken lines are included for the purpose of illustration unclaimed portions of the point of care cart-based ultrasound and form no part of the claimed design.
